ELECTROMAGNETIC DEFLECTING MEANS

Jacques Marie Noël Hanlet, Paris, France, assignor to
J. Visseaux S. A., Paris, France

Application June 29, 1954, Serial No. 440,156

Claims priority, application France September 24, 1953

7 Claims. (Cl. 313—76)

The present invention relates to an improved electromagnetic deflecting means and to the manufacture thereof for deflecting with a high degree of efficiency and without any substantial distorting effect the electron beam of a cathode ray tube, it is therefore an object of the invention to provide an electromagnetic deflecting means adapted to cover the entire angle of 360° around the neck of the cathode ray tube in two halves each covering 180°.

A further object of the invention is to provide such an improved structure of electromagnetic deflecting means that it may advantageously be manufactured by a so-called printed circuit process.

An improved electromagnetic deflecting means according to the invention is mainly characterised in that it consists of at least one pair of coils each spiralled turns of wire extending over a half cylindrical surface and both so serially connected by their outer respective turns that their directions of coiling are opposite with respect to each other; the spiral turns of each coil are so shaped as to avoid any substantial portion thereof extending both parallel to the axis of the cylindrical surface and to any transverse generatrix of this surface.

These and other objects of the invention will be described in detail with reference to the accompanying drawings, wherein:

Fig. 1 schematically shows a conventional arrangement of an electromagnetic deflecting coil means around the neck of a cathode ray tube;

Fig. 2 schematically shows another known arrangement of such an electromagnetic deflecting means;

Fig. 3 shows a theoretical development in a flat plane of an electromagnetic deflecting means such as shown in Fig. 1;

Figs. 4 and 5 show two forms of actual development in a flat plane of an electromagnetic deflecting means according to the invention;

Figs. 6 and 7 illustrate diagrams concerning a first method of manufacturing an electromagnetic deflecting means according to the invention;

Fig. 8 illustrates a diagram concerning a second method of manufacturing an electromagnetic deflecting means according to the invention; and,

Fig. 9 at (a), (b) and at (a) (b) and (a) top rear and cross section views respectively; views of coil elements and their assembly of such electromagnetic deflecting means in the form of a pile such as shown in Fig. 8, before their application upon the neck of a cathode ray tube.

In the representations of Figs. 1 and 2 in the interest of clarity a single turn of wire has been shown for each coil. Similarly, the actual number of turns of wire has been reduced in the following figures.

In Figs. 1 to 5, the reference D denotes either the deflection plane or its intersection line with the plane of the drawing, and the reference H similarly denotes the orthogonal plane thereof, here considered to be a horizontal plane, or its intersection line with the plane of

2

the drawing. The deflecting means is supposed to cause the lateral deflection of an electron beam the axis of which is indicated by the line X—X in its rest position.

All the intersection lines shown in Figs. 3 to 5 must be considered as being taken along generatrices of cylinder 1 of Figs. 1 and 2. This cylinder represents either the neck of a cathode ray tube or a cylindrical insulating support for the electromagnetic deflecting means.

In the form of Fig. 1, each turn of wire of the deflecting means is such that it presents two sides parallel to the direction X—X and two arcuate sides, each approximately covering 180° around the neck of the tube, and extending in respective planes orthogonal to axis X—X. The longitudinal side 2 of the upper turn of wire 15 and the corresponding side 6 of the lower turn cooperate to form an electromagnetic dipole, through which the deflection control current flows in identical directions. The opposite sides 3 and 7 similarly cooperate but the direction of the current therethrough is the reverse of that of the current through the sides 2 and 6. The arcuate sides 4—5 of the upper turn, and 8—9 of the lower turn are quite useless for deflecting purposes; they also introduce, as well known, deleterious effects in the structure of the electron beam passing through the deflecting arrangement: at both ends of this arrangement, this electron beam is distorted by the action of the magnetic fields due to the presence of such arcuate portions of turns. Obviously, a quite substantial loss of supply power occurs in portions of turns as 4—5 and 8—9 since the length of 30 these portions is fairly important in any turn of wire, especially when the deflecting means is to ensure wide angle deflections of the controlled electron beam. For instance, for a cathode ray tube having a deflection angle of 70°, on either side of the D plane, the useful length of any 35 turn of wire in Fig. 1 does not reach 35% of its overall length, and in tubes of recently developed technique, this overall angle of deflection may be made as wide as 90°.

In order to avoid such end distortions of the magnetic deflecting field, it has been proposed to constitute an 40 electromagnetic deflecting means of a pair of crossed coils, or the like, wherein each turn of wire consists of an oval or elliptical line. In Fig. 2, it is apparent that the halves 12—13 and 14—15 on either side of the H plane complement each other in a fashion forming two ellipses 45 intersecting each other and having planes forming an angle θ ; the points of intersection of these ellipses are diametrically opposite with respect to each other, as shown at 10 and 11.

For the same neck diameter, and for the same length 50 along direction X—X, both the arrangements of Figs. 1 and 2 have substantially the same sensibility factor. On the other hand, the overall efficiency is greater for the arrangement of Fig. 2 since the only useless parts of the turns are of reduced length and the distorting effect 55 is also reduced at both ends thereof since the wire lengths generating such distorting fields have been reduced.

According to the invention, an electromagnetic deflecting means is provided with at least one pair of serially connected spirals of opposite winding direction, the series 60 connection being made by their respective outer turns; this pair of spiralled coils form the deflecting means shown in a developed flat form in Figs. 3 to 5, and more specifically, in order to avoid any loss of deflecting power and any distorting end fields, in the developed flat form 65 of Fig. 5. In Fig. 5 the spirals consist of rhombic turns of wire having one diagonal extending along the horizontal or axial direction and the other diagonal extending along the orthogonal direction which, when shaped into arcuate form, will be the direction of the circumference of the neck of the cathode ray tube which is to cooperate with such a deflecting means; the span of the di-

agonal of each spiral extends transversely to such an extent that it will cover 180° on the neck of the cathode ray tube.

In order to carry out the invention, it is also provided to have recourse to the so-called printed circuit technique; this involves depositing or otherwise forming the spiral coils upon a flexible insulating backing, then insulating its bare metallised face, and bending the products thus obtained around the neck of a cathode ray tube or an insulating spacer surrounding this neck.

Alternatively two other processes may be used for manufacturing such printed deflecting means. In the first process, Figs. 6 and 7, a spiral of parallelogrammatic turns of wire is first formed upon a flexible insulating backing, such as shown in Fig. 6, and, after insulating its bare metallised face, this product is folded along the oblique line indicated in Fig. 6. The result is the presentation shown in Fig. 7, assuming the insulating backings are translucent.

In the second process, the double spiral of metallic turns of wire is directly formed on an insulating backing, as shown in Fig. 8.

An insulating film may then be formed over the exposed surface of such an element.

In both these processes, the following may be observed. A thin metallic foil, for instance of a copper foil having a thickness of about $\frac{1}{100}$ of a millimeter, is glued upon a plastic material foil alternatively preferably, it is coated with a dielectric plastic film on one of its faces. This may be obtained by spraying an atomised solution of vinyl chloride or methyl-ethyl-cetone over this face. In this solution, preferably about 30% in weight of a material or product is added, having a higher melting point such as calcium carbonate, anhydrated alumina, silica powder, or the like. The thickness of the dielectric film should not exceed $\frac{1}{100}$ of one millimeter and constitute a base support of suitable mechanical strength.

After this composite foil has been made, a photosensitive film is deposited on the bare metal foil and the picture of print, viz. the spiral or spirals, is impressed thereupon. The product is developed, washed and dried. It is then immersed into an acid containing bath until the unexposed parts of the metal foil are completely dissolved. The copper turns remain in relief with respect to the insulating backing and a suspension of colloidal iron in butyl acetate also containing from 15 to 20% in weight of collodion, is atomized thereupon. In this operation, the colloidal iron fills the intervals between the copper turns of the spiral or spirals, and as a result the thickness of the composite foil is substantially uniform throughout its area.

In some cases, a single element will suffice to bring a complete electromagnetic deflecting means. Generally, however, it will be necessary to pile up a plurality of such double spiralled elements for obtaining a deflecting means of suitable power. In such files, the double spiralled coils must be serially interconnected so that the deflecting current after passing through the two spirals of one element, which are serially connected by their structure, passes in the same direction through the next element of the pile.

In such a case, and especially in the manufacture of a deflecting means from elements such as shown in Fig. 8, it is further provided to realize two sets of elements, such as (a) and (b) in Fig. 9, wherein the relative winding directions are opposite. The connection points or terminals are shown at 16, 17 for the (a) element, and at 18, 19 for the (b) element. For electrically connecting such elements, a thin solder will be made between terminals 17 and 19, then for the following element, between terminals 16 and 18, and so forth, as shown in part (c) of Fig. 9 at 20. Such solder paint may be made by painting the terminals with a mixture of rosin and stannic powder, bringing these painted terminals together and heating the paints by means of a soldering iron. The insulating films

will be burned off at these points. After a suitable number of elements has thus been connected, a moderate squeezing is applied to the pile, in the directions indicated by arrows in Fig. 9(c). In Fig. 9(c), the file is shown before squeezing.

Such an electromagnetic deflecting structure whether consisting of a single element or a piling of such elements, pile may be applied at will around the neck of any cathode ray tube for which it has been designed. As the deflecting current passes through the identical but oppositely wound spirals of each and any element, and due to the high efficiency and almost complete distortion, there is obtained a substantially higher degree of uniformity in the controlling magnetic field than with conventional electromagnetic deflecting means.

Having thus described my invention, I claim:

1. In an electromagnetic deflection structure for the neck of a cathode ray tube, at least one flexible sheeted carrier adapted to extend substantially around said neck and containing at least one pair of oppositely wound flat spiral coils extending over the carrier surface in juxtaposition; the windings of each coil extending over opposite halves of said neck with the outer windings of said coils being connected in series; and means for applying deflecting current to said coils at the inner windings; at least the greater part of said windings having angles other than zero and 90° with the generatrices of said neck.
2. Structure according to claim 1, wherein several pairs of spiral coils supported on carrier sheets are piled upon each other, each pair of coils in said pile being oppositely wound with respect to adjacent pairs of coils in said pile, and means for alternately connecting the center windings of pairs of spiral coils to different coils in the succeeding pairs of coils of said pile.
3. Structure according to claim 1, wherein the windings of each coil are of generally circular shape.
4. Structure according to claim 1, wherein the windings of each coil are of generally rectangular parallelogrammatic shape, one diagonal of the parallelograms being substantially parallel to the generatrices of said cylindrical neck.
5. Structure according to claim 1, wherein the windings of each coil are of generally rectangular oblong parallelogrammatic shape, the diagonals as well as the sides of the parallelograms forming angles other than zero and 90° with the generatrices of said neck.
6. Structure according to claim 1, wherein the windings of each coil are of generally rectangular oblong parallelogrammatic shape, the diagonals as well as the sides of said parallelograms forming angles other than zero and 90° with the generatrices of said neck, each of said coils being formed of two sections separated by a straight line passing through the centers of said parallelograms, said two coil sections being arranged on two coil portions of said carrier sheet superimposed upon each other and attached to each other along said straight separation line.
7. Structure according to claim 1, wherein several pairs of spiral coils supported on carrier sheets are piled upon each other, each pair of coils in said pile being oppositely wound with respect to adjacent pairs of coils in said pile, and means for alternately connecting the center windings of pairs of spiral coils to different coils in succeeding pairs of said pile, said connecting means including a deformation of the carrier sheets at the points of connection.
